CLAIM

The ornamental design for a double handle and clasp for exercise equipment, as shown and described.

DESCRIPTION

FIG. 1 is a right front perspective view of the double handle and clasp for exercise equipment, showing my new design thereof;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line used for the purpose of illustrating ornamental stitching in FIG.'s 1-5 near the clasp to exercise equipment forms a part of the claimed design.

1 Claim, 7 Drawing Sheets
